UNITED STATES PATENT OFFICE.

FREDERICK W. PENDERGAST, OF CAMBRIDGE, MASSACHUSETTS.

MOP-HEAD.

No. 909,449.

Specification of Letters Patent.

Patented Jan. 12, 1909.

Application filed May 8, 1908. Serial No. 431,570.

To all whom it may concern:

Be it known that I, FREDERICK W. PENDERGAST, of Cambridge, in the county of Middlesex and State of Massachusetts, have 5 invented certain new and useful Improvements in Mop-Heads, of which the following is a specification.

This invention relates to a mop head comprising opposed jaws adapted to grasp a 10 mop interposed between them, and provided with means for engagement with a cylindrical rod or handle and with means for adjusting the jaws to cause them to grasp and release the mop.

15 The invention has for its object to provide a simple, durable, and relatively inexpensive mop head, the parts of which are reduced to a minimum, and in which the jaws are capable of being automatically adjusted to variations between the thickness 20 of the edge portions of the interposed mop.

The invention consists in the improvements which I will now proceed to describe and claim.

25 Of the accompanying drawings, Figure 1 represents a side elevation of a mop head embodying my invention, and a portion of the handle to which the head is attached. Fig. 2 represents an end view of the same. 30 Fig. 3 represents a section on line 3—3 of Fig. 1. Fig. 4 represents a section on line 4—4 of Fig. 1. Fig. 5 represents a section on line 5—5 of Fig. 1.

The same letters of reference indicate the 35 same parts in all the figures.

My improved mop head is composed of two elongated jaws 12, 12, each having a shank 13, each jaw and its shank forming a T-shaped piece and being preferably formed 40 as a single casting. The end portions of the jaws, which project from opposite edges of the shanks, are preferably U-shaped in cross section as shown in Fig. 5, each jaw having two narrow biting or grasping edges 14. 45 Each jaw is preferably provided with two end spurs 15 and an intermediate central spur 16, these spurs being adapted to indent a mop inserted between the jaws. The inner sides of the shanks 13 are concave in 50 cross section, and are adapted to bear upon and conform to opposite sides of a cylindrical handle 17. The shank of one of the jaws is provided with an aperture 18, which is preferably elongated crosswise of the shank, the outer surface of this shank being 55 convex in cross section. The elongation of

the aperture 18 and the convex form of the outer side of the apertured shank are important features of my invention as hereafter stated. For the sake of symmetry and 6 lightness, I prefer to make the outer surface of the other shank convex as shown in Fig. 4. The shank, which is not provided with an aperture, is provided with a bolt 19 adapted to pass through the handle 17 and 65 the aperture 18 in the other shank, the outer end portion of the bolt being threaded and provided with a clamping thumb nut 20 which is adapted to bear upon the apertured shank. 70

The nut 20 being loosened, the jaws are permitted to separate sufficiently to receive a mop cloth or fabric between them. After the mop has been inserted between the jaws, the nut 20 is screwed down upon the bolt 75 and causes the jaws to exert a clamping pressure upon the mop. The elongation of the aperture 18 and the convex form of the outer side of the shank in which said aperture is formed, permits said shank to slip 80 laterally upon the handle and enables the accompanying jaw to assume different angles relative to the opposite jaw, as indicated by full and dotted lines in Fig. 2. Provision is thus made for compensating 85 for variations in the thickness of the mop the jaws being enabled to bear with equal pressure upon a mop which is thicker at one edge than at the other. Another advantage of the elongated aperture or slot 18 is the 90 fact that said elongation compensates for any variation of the bolt hole in the handle from a true central position, it being difficult to bore a number of handles with the bolt hole of each in an exactly central position. 95

The formation of the bolt on the shank which carries it, is an advantage because said formation reduces the number of parts and the expense of construction to the minimum, and leaves the outer side of the shank 100 smooth and free from a projecting bolt head which might catch the mop or be otherwise objectionable. The shank on which the bolt is formed constitutes a bolt head having a smooth external surface conforming to the 105 portion of the handle on which said shank bears, as shown in Fig. 4.

I claim:

1. A mop head composed of two opposed jaws having shanks adapted to bear on opposite sides of a cylindrical handle, one of said shanks having an aperture while the 110

other shank has a bolt formed integral therewith and adapted to pass through the handle and through said aperture, and a clamping nut engaged with the outer portion of said bolt and adapted to bear on the apertured shank, the shank on which the bolt is formed constituting a head for said bolt which presents a smooth external surface conforming to the handle.

- 10 2. A mop head composed of two opposed jaws having shanks adapted to bear on opposite sides of a cylindrical handle, one of said shanks being internally concave and externally convex in cross section and provided with an aperture which is elongated crosswise of the shank, the other shank

having a bolt adapted to pass through the handle and through said aperture, and a clamping nut engaged with the outer portion of said bolt, the elongation of the aperture permitting the apertured shank to slip laterally on the handle whereby the jaws are adapted to conform to inequalities in the thickness of a mop interposed between the jaws. 20

25 In testimony whereof I have affixed my signature, in presence of two witnesses.
